SNAP SWITCH

Clarence John Hathorn, St. Marys, Pa., assignor
to The Stackpole Carbon Company, St. Marys,
Pa., a corporation of Pennsylvania

Application January 21, 1937, Serial No. 121,529

6 Claims. (Cl. 200—67)

My invention relates to the control of an electric circuit and relates particularly to a snap switch for completing or interrupting the circuit at the option of the operator.

5 My invention is particularly adapted for use as a switch combined with a volume control wherein both the switch and the volume control are actuated by a single control shaft. An example of a combined unit is shown in my prior Patent No. 2,057,829, granted October 20, 1936. The particular switch under consideration is assembled within a housing whose external diameter is approximately one inch and the thickness of which is approximately one-quarter inch.

10 15 It is an object of my present invention to reduce the number of parts which have heretofore been used in a snap switch.

It is a further object of my invention to eliminate undue sparking or the freezing of the stationary terminals and the movable bridging member.

20 25 It is another object of my invention to have a combined rolling and frictional contact between the fixed contacts and the movable bridging member whereby the main contact surfaces will always be kept clean.

Another object of my invention is to provide a switch wherein the arcing occurs on auxiliary or arcing portions of the contacts, and the main contact is made between surfaces other than those where arcing occurs.

30 35 Another object of my invention is to reduce the size of the movable electrical bridging member so that it may be manufactured in quantity lots at a low cost.

Another object of my invention is to provide a compact snap switch of sturdy construction which may be utilized in combination with a volume control wherein a single control actuates 40 both the switch and the volume control but wherein actuation of the switch to closed circuit position is effected by a relatively small movement of the control in one direction and permitting a relatively large movement in the same direction without effecting the operation of the switch or the switch may be utilized alone.

45 With the above and related objects in view, my invention consists in the details of construction and the combination of parts that will hereinafter be fully described when the description is read in conjunction with the accompanying drawings, in which:—

50 55 Fig. 1 is a plan view of a snap switch embodying my invention.

Fig. 2 is a sectional view taken on the line 2—2 of Fig. 1.

Fig. 3 is an exploded part of the elements comprising my improved snap switch.

Fig. 4 is a plan view of the insulated base. 5 Fig. 5 is a plan view of my snap switch and its actuator.

Fig. 6 is a side view of the device shown in Fig. 5.

Fig. 7 is a plan view of a modification of my 10 invention, the switch being shown in an open circuit position.

Fig. 8 is a plan view of Fig. 7 with a dielectric shield positioned between the actuating spring and the stationary terminal. 15

Fig. 9 is a sectional view taken on the line 9—9 of Fig. 8.

Fig. 10 is a plan view of the dielectric shield alone.

Fig. 11 is a fragmentary enlarged view of the 20 switch shown in Fig. 7.

Fig. 12 is a fragmentary view of Fig. 8 but with the switch partly in closed circuit position.

Fig. 13 is a view of the switch shown in Fig. 8 in closed circuit position. 25

Fig. 14 is a view similar to Fig. 11 but with the switch being in partial open circuit position.

Fig. 15 is a view similar to Fig. 11 but the switch is in partial open circuit position.

Fig. 16 is a plan view of the modified electrical 30 bridging member.

Referring now in greater detail to the drawings, in Fig. 1 is shown a midget type of snap switch wherein the overall diameter of the switch is approximately one inch, and the overall thickness 35 of the base is one-quarter inch.

The switch mechanism hereinafter further described is mounted within a chamber of an insulated base, generally designated as A, which is preferably composed of a molded phenolic 40

45 product. A body portion 10 of the base is substantially flat, and from the base's periphery, which is substantially perpendicular to the flat surface, extends a flange 12 which is circular on its outer curved surface. The flange 12 has a plurality of recesses or notches 14 and 15 on the inner curved portion of the flange, and the recesses communicate with the central chamber of the base. The central chamber is in communication 50 with a bridging member and terminal chamber 16.

The notch 14 and opening 17A receive a pintle 17, and the converging walls 18, 19 partially defining the notch 14 serve as complementary stop members for a switch trigger, generally design- 55

nated as B. The trigger B pivotally mounted on pintle 17 comprises a flat body portion 20, which has openings 22, 23 located at its respective ends. One opening 22 receives a portion of the pintle 17, and the other opening 23 receives a portion 24 of a torsional spring, generally designated as C. Spaced parallel ears 25, 26 are integrally formed from the side edges of the base and extend at right angles to the base of the trigger. Each of the spaced ears 24 or 25 is engaged by an eccentrically mounted stud 27 which oscillates the trigger, hence actuating the switch. The notch 15 enables the coiled portion 28 of the torsional spring C to freely move without engaging any portion of the flange 12 or the base A.

The bridging member and terminal recess 16 receives the contact portions of each of the terminals D and E, and the recess 16 also receives an electrical bridging member, disc, or roller, generally designated as F. The aforementioned elements will be hereinafter further described in considerable detail.

The torsional spring C has a central coiled or closed portion 28, and from the coiled portion extend diverging legs 24 and 29. The spring C has a tendency to expand as well as to rapidly move the electrical bridging disc F from one position to another position.

Movement of the trigger B does not actuate the bridging disc F until the medial axis of the closed end of the spring C passes slightly beyond dead center as the trigger compresses the spring-arms of the torsional spring C together. The energy stored in the spring rapidly moves the contact, either closing the electrical circuit when the terminals D and E are bridged or breaking the circuit when the electrical contact is moved away from the terminals. The tip 30 of leg 29 enters a bore 32 of the cylindrical end 34 of an insulating bushing G; which cylindrical end 34 interfits with a central opening 36 of the electrical disc F. However, the end 34 terminates short of the lower surface of the disc F so that it provides no obstacle to the movement of the roller.

The leg 24 of spring C has an offset therein so that a portion of the spring engages an upper portion of the flat body 20, and a portion of the same leg engages a lower portion of the trigger body so that the leg 24 cannot jump from the trigger.

It is to be noted that the electrical bridging disc F is pressed downwardly on the base and is moved into engagement or away from engagement with the electrical terminals D and E solely by the spring C.

The rigid stationary electrical terminal D made of a single piece of electrical conducting metal has an external eye portion 38 to which an electrical lead wire may be attached. The eye portion merges with a central flat portion 40 which interfits with a complementary opening 42 in the base A, and the main contact surface 44 of the terminal is of a greater width than the width of the intermediate portion 40. The aforementioned structure enables the terminal D to be readily inserted in the opening 42 so that shoulders 45 and 46 abut against the base, and then the outside ends 47 and 48 on the intermediate portion 40 are expanded into engagement with an outside portion of the base. Hence, the terminal is held in position. The main contact portion 44 of the terminal abuts a portion of the vertically extending side wall so that the force exerted by the bridging disc F cannot move the terminal.

The flexible stationary electrical terminal E which is made of suitable electrical conducting material is rigidly held in the base A in a manner similar to that by which fixed terminal D is held. The terminal has an eye in its outside extending portion 50 to which an electrical lead wire may be attached, as by soldering. The eye portion 50 merges with a central flat portion 52, the latter interfits with a complementary opening 54 in the base A. The central portion 52 is integrally connected with a widened portion 56 that provides two shoulders 57, 58 that abut against the base A. Shoulders 60, 61 extending on the outside of the base are expanded to overlap the outside portion of the base so that the terminal cannot move in either a longitudinal or transverse direction. Extending at right angles to the widened portion 56 and integrally formed therewith is an intermediate springlike portion 62 which is limited by the wall 64 of the recess 16 in moving to the left, as Fig. 1 is viewed, but may freely move to the right. From the intermediate portion 62 is the contact disc engaging portion 66 which has a lower extension 68 that abuts the insulating base in the groove 69, and the extension 68 serves to support the end of the flexible extension 66. The disc engaging portion of the flexible terminal E is curved to complementarily engage a portion of the curved bounding surface of the bridging disc F.

It should be noted that in the position illustrated in Fig. 1, the flexible arm 66 is spaced from a wall 70, and the connecting portion 62 is also spaced from its limiting wall 64. However, when the trigger is oscillated to closed circuit position, the roller bridging disc F first engages the fixed terminal D before it engages the flexible terminal, and the arc created when the electrical circuit is opened occurs on a portion of the contact 66 which is not the final surface engaged because the disc F pushes the contact 66 against the wall 70. In other words, arcing occurs between auxiliary portions of each terminal which are not the final or main contact surface.

Repeating the above in other terms, when the circuit is to be broken, it is to be noticed that the flexible terminal contact 66 will follow in direct contact with bridging disc F for a short distance, and the breaking arc will take place near the end 45 of the fixed terminal D.

It is to be particularly observed that the lowermost flat portion 73 of disc F adjacent the curved bounding surface rolls upon a narrow ledge 75, thus minimizing the friction between the base and the disc F. However, the disc F both rolls and frictionally engages or wipes the stationary rigid and flexible terminals D and E. This frictional action smooths or erases any irregularities or obstructions due to oxidation, pitting, or dirt so the contact resistance is kept low. Oxidation, pitting, or dirt generally results in high contact resistance between the terminals and the bridging member.

In order to avoid any flashovers between the spring C and the flexible terminal E, a thin piece 65 of insulation may be placed between such elements in a manner not to obstruct the operation of the switch.

When the disc F is in open electrical circuit position, it rests on the ledge 75 and against the wall 78. The wall 78 is formed in alignment with the contact surface of the fixed terminal D, and the wall is turned at right angles to limit the movement of the disc F in its open circuit position.

A metal cover 74 may be placed over the switch and a control shaft 76 may be suitably journaled to the cover. The cover may be grounded or connected to a point of zero potential in order to reduce any stray electrostatic lines of force or any stray electromagnetic lines of force. The eccentric 27 which engages one or the other of the spaced or bifurcated members 25, 26 is suitably attached to shaft 76 and actuates the trigger B upon actuation of the shaft 76.

However, the switch may be inserted on a volume control as shown in my prior Patent No. 2,057,829 where a single control actuates both the switch and the volume control but wherein actuation of the switch to closed circuit position is effected by a relatively small movement of the control in one direction and permitting a relatively large movement of the control in the same direction without affecting the operation of the switch.

If it should be desired to have the bridging disc slid into position instead of rolled, a notch may be cut into the flange of the insulating bushing G so that arm 29 of spring C lies with the notch. This will lock the electrical bridging disc and the leg of the torsional spring together.

Referring now in greater detail to the modification illustrated in Figs. 7 to 14, I disclose a movable electrical bridging member, generally designated as F¹, which has an irregular curved bounding surface.

The electrical conducting bridging member has an irregular bounding surface, which is arcuate from the points b to c and e to f. The arcuate surface b, c has a radius which is of equal radius to the arcuate surface e, f. From the point b is a tangent which extends to the left as Fig. 16 is viewed and which defines a portion of the flat bounding surface a, b. A similar arrangement is made from the point c which defines the flat surface d, c. Tangent surfaces from the ends of the arcuate surface result in the flat surfaces f, a and e, d. Hence, the bounding surface of the disc is as follows:

The flat surface a, b and the arcuate surface b, c, flat surface c, d, flat surface d, e which is almost at right angles to the surface c, d, and the arcuate surface e, f is the same radius as b, c, and a flat surface f, a which is substantially at right angles to the surface a, b.

The bridging member F¹ functions as follows: When the circuit is partly closed from the initial position of Fig. 11, it will be seen that the bridging member F¹ is rotated slightly so that the flat surface c, d engages and wipes the fixed contact D, and the arcuate surface e, f fits into the bowed portion of the flexible terminal E (see Fig. 12). In the closed circuit position, as illustrated in Fig. 13, the curved surface e, f of the bridging member F¹ is still in contact with the flexible terminal E, and the flat surface c, d has wiped along the fixed contact D.

It is to be noted, however, that the roller or bridging member F¹ is partly rolled into position, and in Fig. 13 the bridging member slides into position. When the switch is actuated to open the circuit, then the arc is broken so that portions of the bridging member which are not used as the main contact surfaces take the arc. The arc will be taken by point c and a portion of the flat surface e, d as the bridging member reaches the curved wall stop portion of the base and adjusts itself as rolling into its nest so that it is in a position of Fig. 7 or 11.

In Fig. 10 I show a shield of a configuration to

fit between the flexible terminal of the fixed terminal, and it lies within the main surface of the base chamber. The shield H has an elongated opening 80 therein which enables the insulating bushing G to freely slide back and forth.

Thus, it is seen that the above-detailed description particularly applies to the illustration of Fig. 8 where the dielectric or insulating shield H is disposed between the live flexible terminals E and the metallic spring C. This dielectric shield 10 reduces any danger of a flashover occurring between the live terminals E and the metallic spring, particularly since the distance between the spring and the flexible member is comparatively small, and if a flashover should occur, the potential 15 difference between the coil portion of the spring and the fixed terminal must be relatively large.

It is also to be known with respect to the structure outlined in Figs. 7 to 16, the stamped-out electrical bridging member is shaped to produce both a rolling and a sliding action whereby the wiping of the contact will always keep the main contact surfaces clean and free from dust or dirt and free from corrosion, and the arcing takes place upon auxiliary contact terminals so 25 that the main contact surfaces will be free from pitting or excessive burning. The clean contact surfaces are features which must be present in the switch so that the effective life of the switch is long, and the clean main surfaces also reduce 30 the contact resistance between the stationary terminals and the movable bridging member considerably.

Although my invention has been described in considerable detail, such description is intended 35 as illustrative rather than limiting, since the invention may be variously embodied, and the scope of the invention is to be determined as claimed.

I claim as my invention:—

1. A snap switch comprising an insulating base, a stationary electrical terminal and a flexible electrical terminal, an electrical bridging disc adapted to engage said terminals whereby the electrical circuit will be closed and to move away 45 from said terminals whereby the electrical circuit will be opened, said disc having an opening therein, a small cylindrical insulating bushing interfitting with the opening in said disc, a flange on said insulating bushing adapted to engage the 50 upper surface of said bridging disc, a forked actuating trigger pivotally mounted, a torsional spring having one end connected to said trigger, and the other end bent at an angle whereby the bent end extends into the insulating bushing, a portion of 55 said spring pressing upon the insulating bushing flange thereby pressing said bridging member in a direction towards the base, and said spring adapted to directly move said bridging disc in one direction or the reverse direction depending 60 upon the movement of said spring beyond its dead center position.

2. A snap switch comprising a base, a plurality of spaced electrical terminals mounted thereon, a rotatable disc-like metal bridging member freely movable across said base into and out of engagement with said terminals, said bridging member being provided with an axial opening perpendicular to said base, a pivoted trigger connected to said base, and a torsional spring having one 65 end connected to the trigger and the other end bent to project loosely into said opening, said spring being adapted to rapidly roll said bridging member into and out of bridging contact with said terminals as said trigger is moved back and 70 75

forth, said spring being the only means for holding the bridging member in position on the base and for actuating it.

3. A snap switch comprising a base, a plurality of spaced electrical terminals mounted thereon, a rotatable disc-like metal bridging member freely movable across said base into and out of engagement with said terminals, said bridging member being provided with an axial opening perpendicular to said base, an insulating bushing disposed in said opening and projecting above the bridging member, said bushing being provided with an axial opening, a pivoted trigger connected to said base, and a torsional spring having one end connected to the trigger and the other end bent to project loosely into said bushing opening, said spring being adapted to rapidly roll said bridging member into and out of bridging contact with said terminals as said trigger is moved back and forth, said spring being the only means for holding the bridging member in position on the base and for actuating it.

4. A snap switch comprising a base, a plurality of spaced electrical terminals mounted thereon, a rotatable disc-like metal bridging member freely movable across said base into and out of engagement with said terminals, said bridging member being provided with an axial opening perpendicular to said base, an insulating bushing disposed in said opening and provided at its outer end with a flange extending radially outwardly across the bridging member, said bushing being provided with an opening perpendicular to said base, a pivoted trigger connected to said base, a substantially U-shaped torsional spring lying in a plane substantially parallel to said base, one end of said spring being pivotally connected to the trigger and the other end being bent substantially at right angles and projecting loosely into said bushing opening, said spring being adapted to rapidly roll said bridging member into and out of bridging contact with said terminals as said trigger is moved back and forth, said spring being the only means for holding the bridging member in position on the base and for actuating it.

nals as said trigger is moved back and forth, said spring being the only means for holding the bridging member in position on the base and for actuating it.

5. A snap switch comprising a base, a plurality of spaced electrical terminals mounted thereon, a rotatable disc-like metal bridging member freely movable across said base into and out of engagement with said terminals, said bridging member being provided with an axial opening perpendicular to said base, a pivoted trigger connected to said base, and a torsional spring having one end connected to the trigger and the other end bent to project loosely into said opening, said spring being adapted to rapidly roll said bridging member into and out of bridging contact with said terminals as said trigger is moved back and forth, said spring being the only means for holding the bridging member in position on the base and for actuating it, and said base defining a guideway for the bridging member.

6. A snap switch comprising a molded insulated base provided with a recess, a pair of spaced electrical terminals mounted in said base at one end of said recess, a rotatable disc-like metal bridging member disposed in said recess and freely movable thereacross into and out of engagement with said terminals, said bridging member being provided with an axial opening perpendicular to said base, a trigger pivoted to said base at one side of said recess, and a torsional spring having one end connected to the trigger and the other end projecting loosely into said opening, said spring being adapted to rapidly roll said bridging member back and forth in said recess and into and out of bridging contact with said terminals as said trigger is oscillated, said spring being the only means for holding the bridging member in position in the recess and for actuating it therein.

CLARENCE JOHN HATHORN.
